UNITED STATES PATENT OFFICE.

WILLIAM P. DUN LANY, OF CLEVELAND, OHIO, ASSIGNOR TO E. L. THURSTON,
TRUSTEE, OF CLEVELAND, OHIO.

TICKET-ISSUING MACHINE.

1,028,199.

Specification of Letters Patent. Patented June 4, 1912.

Application filed May 12, 1910. Serial No. 560,800.

To all whom it may concern:

Be it known that I, WILLIAM P. DUN LANY, a citizen of the United States, residing at Cleveland, in the county of Cuyahoga and State of Ohio, have invented a certain new and useful Improvement in Ticket-Issuing Machines, of which the following is a full, clear, and exact description.

10 This invention relates to improvements in machines, adapted for use by ticket sellers, wherewith any desired number of tickets may be printed and delivered for immediate sale. Machines of this sort may be advantageously used by station agents selling railway tickets, and by the ticket sellers of different kinds of places of amusement, especially amusement parks, so-called, and by persons selling tickets for various other purposes.

15 A practical machine embodying the invention is shown in the accompanying drawings, and hereinafter described, and the novel features thereof constituting the invention are clearly defined by the appended claims.

20 In the drawings, Figure 1 is a left side elevation of the machine. Fig. 2 is a front view thereof. Fig. 3 is an elevation of a 30 part of the right side of the machine. Fig. 4 is a sectional side elevation; and Fig. 5 is a rear view of said machine.

25 In the machine are two rotatable printing cylinders D and E, which are respectively fixed to the parallel shafts d and e, extending between and rotatably mounted in the two side members a, a, of the framework of the machine. Two rotatable platen rolls B and F are respectively associated with these 35 printing cylinders, said rolls being fixed to the shafts b and f. Preferably these shafts are mounted in boxes which are slidably mounted on said frame members a, a, and are spring pressed toward the associated 40 printing cylinders. As the parts are arranged the printing cylinder D is above, and the printing cylinder E is below the horizontal plane in which the paper strip I goes through the machine; and, of course, 45 the platen rolls are respectively below and

above said plane. The cylinder D therefore prints on one side of the paper strip and the cylinder E prints on the other side thereof. These printing cylinders and platen rolls are to be turned at like speeds 55 by suitable mechanism so as to draw the paper strip I through the machine the required distance to print one ticket or more, as required. The mechanism shown for turning these parts the required distance includes the following: Attached to the shafts d and f respectively are the pinions d' and f', both of which mesh with a gear H rotatably mounted on a stub shaft h fixed to one of the side frame members a. Two 60 pinions b' and e' are respectively fixed to the two shafts b and e and both mesh with gear K, which gear is fixed to one end of a shaft k which is rotatably mounted in the two side frame members. The gears H 65 and K are the same size and mesh with each other. A pinion k' is fixed to the opposite end of the shaft k. This meshes with a pinion J rotatably mounted on one of the frame members. A ratchet j is fixed to this 70 pinion; and an operating lever O mounted concentric with the ratchet j carries a pawl o for engagement with said ratchet. Preferably a treadle L is connected by a link o' with the lever O; and a spring l' restores 75 the treadle and lever O to their normal positions.

At the front side of the machine is a fixed plate a' having through it a slot a² through which the printed ticket strip I is delivered. 80 Pivoted to this plate is a knife bar P adapted to be swung across the slot a² and cut off the projecting part of the ticket strip. One end of this lever lies under the operation lever O, and the other end lies in a position 85 to be struck by another lever to be presently described. When lever O is moved down far enough it will strike the knife bar and swing it down and thereby cut off the projecting part of the ticket strip. But just before this lever O begins to move the knife bar, a toe o² on the pawl o strikes a fixed pin a⁴ and thereby the pawl is withdrawn from its engagement with the ratchet. When 90 this has been done the printing cylinders 95 100

and platen rolls will have been turned far enough to carry forward a length of the paper strip apportioned to one ticket. When, now, the operating lever O is moved 5 down a little farther, it will operate the knife bar, as stated, but will not cause any further forward movement of the ticket strip.

It is desirable that the machine be provided with means for printing and delivering a strip of tickets having perforations between them, the number of tickets in this strip being the number commonly purchased. The machine as shown is adapted 10 to deliver a strip of five of such tickets and to cut off that strip. To accomplish that result a gear Q is loosely mounted on the same stub shaft h on which the gear H is mounted. This gear Q carries a pawl q 15 which engages with a ratchet H' fixed to the gear H. A disk M pivoted to one of the frame members has a gear segment m which engages with the gear Q, and it likewise has an arcual slot m' through which 20 projects a fixed pin a⁵. Hung concentrically with this disk is a lever N. It is connected below its center by means of a stiff spring m² with the disk N. By swinging this lever to the left, as shown in Fig. 1, the 25 disk will be turned through an arc corresponding with the length of the slot m'; and this will result, through the action of the train of mechanism described, in turning the printing rolls, etc., far enough to feed forward as much of the paper strip 30 as is required for five tickets. When the disk is stopped by the engagement with the end of the slot m' with the pin a⁵, the lever N is permitted, by extending the spring m², 35 to move a little farther, and this movement will bring the end of an arm n fixed to the lever N against the knife bar P which will, therefore, be rocked so as to cut off the ticket strip which has been fed through 40 slot a².

Each of the printing cylinders may be provided with any required printing surfaces; and the matter to appear upon a ticket may be extended over any required 45 part of the surface of the cylinder, provided the intermeshing gears and pinions and other operating mechanism described are so relatively proportioned that the printing cylinders will be given a corresponding 50 arcual movement by means of the lever O, when operated as stated. In the particular construction shown the parts are so constructed and arranged that the matter to be printed on each ticket occupies about one 55 circumferential half of each cylinder, wherefore a ticket is printed during each 60 half revolution of the printing cylinders.

The cylinder E is that cylinder which

prints what may be styled the face of the ticket. There are two plates T, T, each extending circumferentially nearly half way around the cylinder and these plates are held by any appropriate means upon said cylinder. Each will preferably carry the same design or printing face,--which shall include the name of the amusement place, or company in whose behalf the tickets are to be sold. Preferably also the ends, circumferentially considered, of these plates are beveled, and fit beneath the undercut circumferential ends of recesses formed in the surface of said cylinder. Between the proximate ends of these printing plates, two longitudinal slots e³ are formed in the surface of the cylinder. On the platen roll F are two longitudinally extended perforating blades S, these being fixed diametrically opposite to each other and projecting radially outward. As the printing cylinder and platen roll are turned these perforating blades will perforate the ticket strip passing between them, the blades entering said slots. Preferably the slots are somewhat enlarged a little back of the surface of the cylinder, and in these enlargements wood blocks U are placed, which blocks are spring pressed outward.

Fixed to the upper part of the framework between the frame members a, a, is a numbering machine of ordinary construction. Its operating shaft V has fixed to it the usual star-wheel v which is arranged so as to be struck and turned by the fingers f² fixed to the platen roll as the latter is turned. There are two of these fingers, so that this star wheel is struck twice during each revolution of this platen roll. Or, in other words, it is moved as often as a ticket is printed.

There are reasons, which it is perhaps unnecessary here to explain, why the managers of amusement resorts and railway companies desire that their tickets shall not only bear the date of issue, but that they shall also bear some code indication whose significance shall be unknown to the general public, or to the ticket-seller. It is also desirable that the tickets shall bear consecutive numbers, and it is also thought to be desirable that the tickets shall be numbered in two series rather than in one only. The machine shown is organized with special reference to meeting these demands. In the cylinder D is a longitudinally extended recess d³. In this recess two ordinary numbering machines are secured so that their number printing wheels shall project to the cylindrical printing surface of the cylinder. Each of these numbering machines is provided with an operating shaft W, to the outer end of which a star wheel w is fixed,--

this star wheel being in such position that it will engage during each revolution of the cylinder with a fixed pin a^6 . In the 5 surface of cylinder D and in each half there- of there are longitudinally extended grooves having undercut ends circumferentially considered. Removable printing plates Y are provided and constructed with beveled ends, so that they may readily be inserted into 10 these grooves or readily removed therefrom, as required. Upon these plates any combination of type symbols or numbers may be placed. It is very clear that therefore the tickets may be printed not only with the 15 usual design on one surface, as by cylinder E, but with consecutive numbers of date and any secret code sign on the reverse side.

The ink may be supplied to each of the cylinders by means of an ink well Z which 20 lies between and is pivoted to the frame members a , a , and is provided with a series of rollers of which the terminal roller z engages with the surface of the associated printing cylinder. A spring z' may hold 25 this ink-well frame and the cylinders mounted thereon in operative position, as shown.

It will be understood from the foregoing that whenever it is desired to print and issue one ticket with the described machine 30 the operator presses down the treadle. When it is desired to issue a strip of five perforated tickets he takes hold of the lever N and swings it as far as he can, whereby the printing mechanism will be turned far 35 enough to print five tickets, and the knife will be operated to cut off the strip of five tickets.

Having described my invention, I claim:

1. In a machine for printing and issuing 40 tickets, the combination of a suitable frame, two printing cylinders, two platen rolls associated respectively with said printing cylinders and located one roll over its associated cylinder and one roll below its associated cylinder, means for simultaneously rotating the two rolls and the two cylinders at the same surface rate, two trains of mechanism for rotating said cylinders and rolls, and means limiting the range of movement of said trains of mechanisms whereby one may turn said cylinders and rolls through a greater arc than the other.

2. In a ticket printing and issuing machine, the combination of a printing cylinder, a platen roll, a plate having a slot substantially aligned with the plane of contact of said cylinder and roll, a pivoted knife movable across said slot, a lever pivoted upon an axis at right angles to the knife, operative connections between the lever and printing and platen rolls, the said lever operating the said rolls throughout a portion of its path of movement, and during a cer-

tain portion of its movement ceasing to operate said rolls, at which time, it engages 65 the knife to operate the same.

3. In a ticket printing and issuing machine, the combination of two printing cylinders, two platen rolls respectively associated therewith, a train of gearing for 70 simultaneously turning said platen rolls and cylinders, a slotted plate, a knife movable across the slot in said plate, two levers each adapted when swung to engage with and move said knife, and mechanism respectively operated by said two levers for moving said train of gearing through different arcual distances.

4. In a ticket issuing and printing machine, the combination of a printing cylinder, a platen roll, a slotted plate, and a knife movable across the slot in said plate, a train of gearing for simultaneously turning said cylinder and roll at like surface speeds, a lever pivoted concentrically with the terminal member of said train of gears, a spring connecting said lever and terminal member, means limiting the arcual movement of said terminal member, the lever having an arm adapted to engage with and move said knife.

5. In a ticket issuing and printing machine, the combination of a printing cylinder, a platen roll, a slotted plate, and a knife movable across the slot in said plate, 95 a train of gearing for simultaneously turning said cylinder and roll at like surface speeds, a lever pivoted concentrically with the terminal member of said train of gearing, a spring connecting said lever and terminal member, means limiting the arcual movement of said terminal member, the lever having an arm adapted to engage with and move said knife, said train of gearing including a ratchet and pawl.

6. In a ticket printing and issuing machine, the combination of a rotatable printing cylinder, an associated rotatable platen roll, a slotted plate, a knife bar movable across the slot in said plate, a train of 110 mechanism for turning the cylinder and roll simultaneously in opposite directions and at equal surface speeds, a lever for operating said train of mechanism and having a ratchet and pawl connection therewith and being adapted also to operate said knife bar, and means for disconnecting the ratchet and pawl when said train of mechanism has been sufficiently turned and before the lever operates the knife bar.

7. In a ticket printing and issuing machine, the combination of a rotatable printing cylinder, a platen roll, pinions rigidly connected therewith, two intermeshing gears which respectively engage with said 125 pinions, a gear loosely mounted concentric

4
with one of the last mentioned gears and having a ratchet and pawl connection therewith, a disk having gear teeth on its edge which mesh with said loosely mounted gear and having also an arcual slot, a fixed pin projecting into said slot, a lever mounted concentrically with said disk, a spring connection between the disk and lever, a slotted plate, a knife movable across the slot in said

10 plate and arranged to be engaged and moved by a part of said lever after said disk has been stopped by the engagement of said fixed pin and one end of the arcual slot.

In testimony whereof, I hereunto affix my signature in the presence of two witnesses. 15

WILLIAM P. DUN LANY.
